ELECTRONIC INFORMATION-STORING DEVICES

Frederic Calland Williams, Timperley, and Tom Kilburn, Davyhulme, Manchester, England, assignors to National Research Development Corporation, London, England

Application November 7, 1950, Serial No. 194,414

Claims priority, application Great Britain November 22, 1949

15 Claims. (Cl. 315—12)

This invention relates to a method of and means for storing information of the kind employing a cathode ray tube having an insulating screen, a positive charge being generated at a selected region of the screen surface, owing to the liberation of secondary electrons from the region by the cathode ray beam, in order to record one item of information, and a second item of information being recorded when required by subsequently reducing the positive charge at the region by the further liberation of secondary electrons to the region.

Examples of methods of this kind are described, for instance, in U. S. patent appln. Serial No. 165,622, filed June 2, 1950, which has been abandoned in favor of the continuation thereof, application Serial No. 353,819, filed May 8, 1953, by Frederic C. Williams et al., now U. S. Patent 2,709,230 granted May 27, 1955.

The present invention has for its object to provide a new or improved method and means of the kind set forth.

According to the present invention there is provided apparatus comprising means for deflecting the beam at the said region in order to generate a positive charge along a strip of the screen, means for directing the beam to bombard a spot on the screen on or near the strip in order to reduce the positive charge on the strip by the release of secondary emission thereto, and control means for causing or permitting the bombardment of said spot or preventing such bombardment according to the nature of the information to be stored.

The present invention also provides a method of storing information comprising directing the cathode ray beam recurrently upon a region of the screen, intensifying said beam when directed upon said region, deflecting the intensified beam over a strip upon said screen to generate a positive charge on said strip and thereby record one kind of information, when required to record a second kind of information subsequently intensifying said beam upon a spot of the screen to liberate secondary electrons to reduce said positive charge, and applying signals generated on a pick-up plate associated with the screen, and corresponding to changes in the charge upon the screen, to control the intensification of said beam to regenerate the charge upon said strip.

The speed of deflection along the strip is made slow enough to ensure that the creation of the positive charge is complete but fast enough to ensure that there is no substantial reduction of the positive charge set up at the first part of the strip scanned, by the secondary electrons liberated during the scanning and falling on the part of the strip previously scanned. The speed of scanning will depend on the particular operating conditions of the cathode ray tube. The question of scanning speeds is discussed at length in a paper entitled "A storage system for use with binary-digital computing machines" in the Proceedings of the Institution of Electrical Engineers, part III, No. 40, March 1949, pp. 81-100.

The scanned strip may conveniently be substantially straight.

2

The invention will now be described with reference to the accompanying drawings in which:

Figures 1 and 2 are diagrams illustrating the principle of the invention,

5 Figure 3 shows waveforms of potentials that may be used for carrying the invention into effect, and

Figure 4 is a block circuit diagram of one embodiment of the invention.

In Figure 1, 2 represents a strip on the insulating sur-

10 face of a screen of a storage tube scanned by an electron beam to leave a trough of positive charge as indicated by the graph of Figure 2 at 3. This charge may be left unmodified and may then represent, say, the digit 0.

At 4 in Figure 1 there is represented a strip which is

15 first scanned to leave a trough of positive charge, as in the case of the strip 2, and is then irradiated at a spot 5 to liberate more secondary electrons which wholly or partially "fill up" the trough of positive charge along the strip 4, except, of course, at the spot 5. The resulting charge is indicated in Figure 2 by the graph at 6, the dotted line 7 indicating the positive charge before it was reduced by the further liberation of secondary electrons from the spot 5. This modified form of charge distribution may then represent the digit 1. The secondary electrons which reduce the positive charge on the strip may be liberated from a spot outside the strip so long as the spot is close enough for the neutralisation of charge to take place.

One embodiment of the invention will now be described

30 with reference to Figures 3 and 4.

In Figure 4, a cathode ray tube 10 has upon an end wall the usual screen 11 of phosphor. A pulse generator 20 generates pulses to control and synchronise the generation of the various waveforms required for operating the circuit. Thus after frequency division at 21 the pulses control X and Y-scan generators 22 and 23 which may generate and apply to deflecting means 17 and 18 respectively such waveforms as will cause the cathode ray beam to scan a raster on the screen 11: the X-scan

40 waveform is preferably "paused" as shown in Figure 3(f), the beam thus moving in a series of steps and pausing between the steps.

Pulses from 20 also control the generation by a dot generator 24 of a waveform as in Figure 3(a) and by a dash generator 26 generating a positive-going pulse over the recurrent time interval t_0 to t_2 . A meditation pulse generator 32 generates negative-going pulses in the recurrent interval t_1 to t_2 and these pulses combined with those of Figure 3(a) give rise to the dash waveform of Figure 3(b). The pulses from 24, 26, 32 and from a strobe pulse generator 28 are applied to a gate circuit which operates in a manner more fully described in the specification of U. S. pat. appln. Serial No. 165,262, filed May 31, 1950. Briefly the dot waveform of Figure 3(a) is normally applied to the grid 13 of the tube 10 from the gate 25 and may represent the quantity 0. When it is desired to record the quantity 1, a suitable "write" voltage is applied at 29 to open the gate 25 to the passage of a dash pulse from the generator 26, and the waveform applied to the grid 13 is then changed to the dash and meditation waveform of Figure 3(b). The dot and dash waveform generators 24 and 26 constitute switching means since they generate pulses which determine the times at which the beam is switched on and off.

65 The gate 25 is also controlled by voltages from a pick-up plate 19 upon the outside of the wall of the tube 10 and electrostatically coupled to the screen 11. These voltages after amplification at 27 and strobing by pulses from 28 are arranged to be of one polarity or the other 70 according as the beam is switched on to bombard a spot on the screen which bears a charge as in Figure 2 at 3 or 6 and the polarity is arranged to determine whether, in

the absence of signals applied at 29, the waveform applied to 13 shall be the dot or the dash waveform. In this way, as fully explained on the earlier specification, the charge on the screen 11 can be regenerated in the absence of signals applied at 29 and changed when required by signals applied at 29. Such signals may for example be received from a computor to which "read" signals are applied from a terminal 30, the latter signals representing the stored information. The gate 25 constitutes a selecting means responsive to a "write" voltage applied at 29 or to a voltage applied thereto from the pickup plate 19 to select the dash waveform for application to the beam intensity control electrode 13.

In addition to the beam deflections already described, means which may be separate from but are conveniently associated with the normal scanning means 17, 18, 22, 23, are provided for deflecting the beam while it is turned on during the interval t_0 to t_1 . A waveform suitable for effecting this deflection is shown in Figure 3(c) and it may be generated by a circuit 33, combined with the Y scan voltage from 23 and applied to the Y deflecting plates 18. It is, however, not necessary that the deflection should be in the Y direction but it is preferably at an angle to the X direction. The waveform of Figure 3(c) may be produced by the addition of a saw-tooth wave as in Figure 3(d) and an amplitude-limited pulse as shown in Figure 3(e).

When the dot waveform is applied from the generator 24 to the grid 13 in Figure 4 the beam is switched on only from t_0 to t_1 (and at corresponding later times) and during this time the beam is deflected by the voltage of Figure 3(c) at right angles to the X direction whilst the beam is stationary in the X direction. The conditions are, therefore, as indicated at 2 in Figure 1 and 3 in Figure 2.

When the dash waveform is applied from the generator 26 to the grid 13, the same conditions as with a dot are first produced and then, while the beam is still held stationary in the X direction, it is switched on from t_2 to t_3 , thus producing the conditions represented in Figure 2 at 6.

When the beam is next switched on upon a region charged as at 3 in Figure 2 it may be arranged to generate in the plate 19 a negative pulse, during the strobe interval determined by the pulses from 28. When the beam is next switched on upon a region charged as at 6 in Figure 2 it will generate a positive pulse. These pulses, amplified at 27, are applied to the gate 25 and control regeneration as already described.

The slope of the deflecting wave of Figure 3(c) during the time t_0 to t_1 is made such that the beam is deflected fast enough to prevent any considerable neutralisation of the positive charge behind the beam.

We claim:

1. A method of storing information in which a cathode ray beam is caused to strike a surface of an insulator and to produce a positive charge on such surface by the liberation of secondary electrons, the method comprising storing one kind of information by sweeping the beam along a strip of the surface to produce a positive charge along the strip and, when required, converting the said positive charge to another charge condition representative of a second kind of information by bombarding with the cathode ray beam a spot on the surface on or near the strip from which spot secondary electrons pass to the strip and reduce the positive charge thereon.

2. A method according to claim 1, wherein the said sweeping of the beam is at a speed high enough to prevent substantial reduction, by secondary emission, of the positive charge behind the beam.

3. A method of storing information and of regenerating the store employing a cathode ray tube having an insulating screen and a pick-up plate electrostatically coupled to said screen, said method comprising directing the cathode ray beam recurrently upon a region of the

screen, intensifying said beam when directed upon said region, deflecting the intensified beam over a strip upon said screen to generate a positive charge on said strip and thereby record one kind of information, when required to record a second kind of information subsequently intensifying said beam upon a spot of the screen to liberate secondary electrons to reduce said positive charge, and applying signals generated on said pick-up plate to control the intensification of said beam to regenerate the charge upon said strip.

4. Apparatus for storing information comprising a cathode ray tube, an electric charge-retaining surface within said tube, electron beam producing means including beam intensity control means in said tube, means to sweep the beam recurrently along a track upon said surface, means coupled to said beam intensity control means to intensify the beam for short periods at predetermined regions along said track to produce positively charged strips on said screen, means coupled to said beam intensity control means to re-intensify the beam at spots upon said screen to liberate secondary electrons to reduce said positive charge at said regions, gating means to control the operation of said re-intensifying means to regulate said re-intensification, and means to apply information to be stored to said gating means.

5. Apparatus according to claim 4, comprising means to deflect said beam at each of said regions at an angle to said track, whereby said strips are at an angle to said track.

6. Apparatus according to claim 5, wherein said angle is approximately a right angle.

7. Apparatus according to claim 4, comprising a pick-up plate electrostatically coupled to said screen and means to apply signals generated on said plate, according to their nature, to said gating means to permit and prevent said re-intensification and thereby regenerate the appropriate charge upon said region.

8. Apparatus for storing information comprising an electric charge-retaining surface, a source of electrons, means accelerating electrons in a beam from said source toward said surface, deflecting means adjacent said beam causing said beam to scan said surface in a raster of substantially parallel lines and deflection control means coupled to said deflecting means and causing said beam to sweep said surface in a plurality of strips at a predetermined angle to said substantially parallel lines during the beam scanning over each of said lines, including beam intensity control means, first signal means coupled to said intensity control means and causing said screen to be bombarded along one of said plurality of angular strips when a first information is to be stored, and second signal means coupled to said intensity control means, said second means causing said screen to be bombarded along one of said plurality of angular strips followed by a further bombardment in the region of said strip when a second information is to be stored, each of said first and second signal means being coupled to said intensity control means through a gate circuit, a pick-up plate adjacent said storage surface and coupled to said gate circuit, the signals in said pick-up plate causing said gate circuit to selectively pass signals from said first and second signal means to regenerate information upon said storage surface.

9. The apparatus of claim 8 in which said deflecting means includes a generator of voltage of stepped waveform which causes each of said substantially parallel lines to be scanned in an intermittent motion of starts and stops, said deflection control means being operative to effect said angular sweep during each of said stops in scanning.

10. Apparatus for storing information comprising a cathode ray tube, an electric charge-retaining surface within said tube, means for deflecting the cathode ray beam of said tube, means for controlling the intensity of said beam, a first electric generator generating an ap-

proximately sawtooth waveform extending between upper and lower limiting values, means to apply said waveform to said deflecting means, means for generating two switching waveforms for application to said beam intensity controlling means, one of said switching waveforms causing the beam to be switched on during one excursion of said sawtooth waveform between said limiting values and then to be switched off, and the other of said switching waveforms causing the beam to be switched on during one excursion of said saw-tooth waveform between said limiting values and also, subsequently, when said sawtooth waveform is at a value between said upper and lower limiting values, and selecting means responsive to the information to be stored to apply said switching waveform selectively to said beam intensity control means according to the information to be stored.

11. Apparatus according to claim 10, including a pick-up plate capacitively coupled to said surface and means for applying signals from said pick-up plate to said selecting means to select the one of said waveforms to be applied to said beam intensity control means.

12. Apparatus for storing information comprising an electric charge-retaining surface, a source of electrons, means accelerating electrons from said source in a beam towards said surface, first deflecting means for deflecting said beam in a first direction, a scanning oscillation generator to generate a stepped waveform comprising a series of steps of different, substantially constant values, means to apply said waveform to said deflecting means to deflect said beam in said direction in steps between which the beam is substantially stationary, second deflecting means for deflecting said beam in a second direction at a predetermined angle to said first direction, a second oscillation generator generating a second deflecting waveform having varying portions separated by portions of substantially constant value, said varying portions occurring during said steps of substantially constant values respectively, and means to apply said second deflecting waveform to said second deflecting means.

13. Apparatus according to claim 12, including gating means, a first beam switching means coupled to said gating means and causing said surface to be bombarded substantially only during said varying portions of the second deflecting waveform when a first information is to be stored, and second beam switching means coupled to said gating means and causing said surface to be bombarded during said varying portions and during at least a part of the next succeeding portion of substantially constant value in said second deflecting waveform when a second information is to be stored.

14. Apparatus according to claim 12, including selecting means, first control means coupled to said selecting means and when operative causing said surface to be bombarded substantially only during said varying portions of the second deflecting waveform, and second control means coupled to said selecting means and when operative causing said surface to be bombarded during said varying portions and during at least a part of the next succeeding portion of substantially constant value in said second deflecting waveform, said selecting means being responsive to information to be stored to select the one of said first and second control means which is made operative.

15. Apparatus according to claim 14, including a pick-up plate capacitively coupled to said surface and means for applying signals generated in said pickup plate to said selecting means to select the one of said first and second control means which is made operative.
